UNITED STATES PATENT OFFICE

ALBERT CHAMPION, DECEASED, LATE OF FLINT, MICHIGAN, BY BASIL W. DE GUICHARD, OF FLINT, MICHIGAN, AND DETROIT TRUST COMPANY, OF DETROIT, MICHIGAN, EXECUTORS, ASSIGNEES TO A C SPARK PLUG COMPANY, OF FLINT, MICHIGAN, A CORPORATION OF MICHIGAN

INSTRUMENT PANEL

Application filed February 23, 1928. Serial No. 256,435.

This invention relates to an instrument panel of the type commonly used on the dashboard of an automotive vehicle.

It is an object of the invention to provide a new and improved instrument panel which will obviate separate provision of many of the parts hitherto considered necessary in the manufacture of instrument panels. This is accomplished by forming the panel by die casting and thus lower the cost of manufacturing by forming the main part of the panel from a single element.

It is a further object of the invention to provide a panel of this type which is constructed so that the instruments fixed thereto may be lighted by means of internal illumination, that is, from a light bulb which is not visible from the front seat of the car.

One of the particular advantages of the improved instrument panel resides in the fact that it is constructed to provide a dustproof housing for an instrument, it being sufficient that the mechanism of the instrument be fixed relative to a flat plate. This construction renders the instruments readily removable and the mechanism therein readily accessible for repair work when the plate is removed.

Other objects and advantages of the invention will appear in the course of the following description, taken in connection with the accompanying drawing and appended claims.

In the drawing:

Figure 1 is rear elevation.

Figure 2 is a section on the line 2—2 of Figure 1.

Figure 3 is a section on the line 3—3 of Figure 2, with parts broken away and instruments eliminated.

Figure 4 illustrates a lower central housing cover plate detached from the assembly.

Referring to the drawing, there is illustrated a portion of a dashboard 10 which is provided with an aperture 14 shaped to receive the instrument panel. The aperture and panel in the present case are oval, though it is obvious that they may be of any usual or desired shape.

The novel panel illustrated comprises an integral face 12; and this is shown as pro-

vided, about its periphery, with a separate bezel 16, and as provided on its forward side, with forwardly extending integral housings 20, 22, 24 and 26. In this description the word "forward" is used to denote the side 55 of the panel toward the forward end of the car. The illustrated bezel extends outward beyond the main portion of the face 12, thus providing a peripheral shoulder 30 which abuts against the rear or visibly exposed face 60 of the dashboard. With this construction, assuming the bezel to be initially secured to the panel, the panel may be placed within the aperture 14 from the rear side only, the shoulder 30 holding the panel against further forward movement. 65

Although any method of casting the panel may be used, it is preferred to use die-casting, this being a method that gives a product which requires a minimum of finishing operations. 70

The arrangement of the housings may be varied within wide limits, depending upon the number and character of the instruments it is desired to carry. In the illustrated embodiment, the housing 20 is designed to carry the speedometer 21, housing 22 the ammeter 23, housing 24 the oil pressure gauge 25, and housing 26 the clock 27. 75

The speedometer 21 is shown as provided, 80 about its periphery, with an annular shoulder 34; and this may be adapted to rest directly against the housing 20. A ring 36 may surround the speedometer in front of the shoulder 34 and may be provided with apertured ears 38, shown as arranged to register with ears 40, provided upon the housing 20. Screws 42 are shown as extending through ears 38 and threaded into the casting ears 40, these mentioned parts serving 85 as one suitable means for holding the speedometer firmly within the housing. Housing 20 is shown as provided with a circumferentially extending slot 44, which registers with 90 a similar slot 46 in the side of the speedometer case. A transparent strip 45 of pyraline or similar material is preferably fixed to the outer side of housing 20, over the slot 44, to prevent the entrance of dust. The clock 27 95 100

may be mounted in exactly the same way as the speedometer, so that a description thereof would be substantially a repetition.

It may be noted that in the form shown, 5 housing 24 extends forward slightly farther than housings 20 and 26. This arrangement may be provided in order favorably to support and to protect parts of an instrument mechanism which is not provided with a case 10 and which is capable of being mounted on a mere plate. The plate 48 carries an instrument mechanism 50 (in this case an oil gauge) and dial 52 over which a needle 54 operates. Plate 48 is shown as provided with two op- 15 positely placed and suitably apertured ears 56, registering with ears 58 of housing 24 and adapted to receive screws 60, threaded into the ears 58 for holding the instrument within the housing. A circumferentially ex- 20 tending slot 62 is shown as provided in the side of housing 24 for admitting light, and this slot is preferably covered by the usual strip of pyraline 64 for preventing the entrance of dust. This arrangement obviates 25 the necessity of providing a separate case for the instrument and renders the mechanism immediately accessible for repair upon removal of the plate 48.

In the illustrated embodiment a single light 30 socket is supported from the cover plate 48. By reference to Figures 2 and 4 it will be seen that cover plate 48 may be provided with an extension 68, formed with a central aperture. Welded to the front side of the extension 68 35 is shown an annular bracket 70, provided with spring fingers 72 for removably supporting a light socket 74 shown as extending through the aperture in extension 68 and as adapted to hold a light source such as a bulb 40 76, as thus disposed between bushings, preferably. The light bulb 76 extends inward adjacent the front side of the panel face 12, thus locating the filament even with the slots in the sides of the housings. If desired, 45 the bracket 70 may be welded to the front side of the face of the panel itself. In this connection it may be noted that all the slots are provided in the sides of the housings toward the light bulb.

50 Housing 22 and the means for fastening an instrument therein may be the same as that described with respect to housing 24, except that the cover plate is not shown as provided with any extension carrying a light socket.

55 The face of the panel is formed with openings 80, corresponding to the locations of the housings, for exposing the dials of the instruments. A slightly protruding annular shoulder 82 is preferably provided on the instrument face about each opening 80. While each instrument may be provided with a separate glass face plate, it is preferred to provide a single plate for tightly covering the faces of 60 all the instruments. Fitting within the bezel

16, herein assumed to be separate from panel 12 and flush up against the shoulders 82 is shown a common glass cover plate 84. Small openings are shown as provided in the face of the panel at spaced intervals just within the bezel 16 and extending through these openings are fingers 86, which may be shown integral with a polished metal ring 88, lying against the glass plate 84 just within the bezel 16. On the forward or concealed side, the fingers may be bent over the edge of the panel to hold the glass plate 84 in position. 70 75

75 On each end of the panel is shown a threaded boss 90, formed integrally with the panel, which may extend through a hole in an L-shaped bracket 92. One end of this bracket is shown as engaging the front side of the panel while the other end abuts against the dashboard 10. By tightening nuts 94, the panel is held firmly on the dashboard. 80 85

What is claimed is:

1. An instrument panel comprising an apertured face and an instrument housing integrally cast together, and means for supporting a light source opposite said housing, instrument mechanism being mounted within the housing and said housing being provided with means for admitting light to said mechanism from said source. 90

2. An instrument panel comprising an apertured face and a plurality of instrument housings integrally cast together, instrument mechanisms being supported within the respective housings, a light source being disposed therebetween, each housing being provided with a slot for admitting light to the mechanism therein, and said slots being located so that they open from the housings toward said light source. 95 100

3. An instrument panel comprising an apertured face and a bezel extending about the periphery thereof, said panel being provided with spaced openings therethrough adjacent the inner side of said bezel, a transparent cover fitting within said bezel and covering said apertures and a retaining ring within said bezel over said cover and provided with a plurality of fingers, each finger extending through one of said spaced openings for retaining said ring and cover in position. 105 110

4. An instrument panel comprising an apertured face and a plurality of instrument housings integrally cast together and shaped to be tightly covered by a common glass plate provided with a slot for admitting light to said mechanism, an instrument extending within said housing and fixed thereto, said instrument being provided with an opening corresponding to the slot in said housing. 115 120 125

5. An instrument panel comprising an apertured face and a plurality of instrument housings integrally cast together; and instrument casings in said housings,—said hous- 130

ings and said instrument casings being provided with registering openings for the lateral admission of light to instrument parts within said casing.

5   BASIL W. de GUICHARD,
                         DETROIT TRUST COMPANY,
                         By McPHERSON BROWNING,
                         President,
                         Executors of Albert Champion, Deceased.
